UNITED STATES PATENT OFFICE.

THOMAS MURDOCH, OF MIDDLETOWN, CONNECTICUT.

GUIDE FOR ROCK-DRILLS.

SPECIFICATION forming part of Letters Patent No. 364,278, dated June 7, 1887.

Application filed March 28, 1887. Serial No. 232,619. (No model.)

To all whom it may concern:

Be it known that I, THOMAS MURDOCH, of Middletown, in the county of Middlesex and State of Connecticut, have invented certain

5 new and useful Improvements in Guides for Rock-Drills, of which the following is a full, clear, and exact description, whereby any one skilled in the art can make and use the same.

My invention relates to the class of devices 10 that are used for reaming out holes that have been drilled in rock for blasting purposes; and its object is to provide a device by means of which the accuracy of the reaming may be insured.

15 In making a cut for rock-blasting a number of round holes are drilled in a straight line at convenient intervals, these holes being all in a common plane that conforms to the plane on which it is desired to separate the rock by 20 blasting. After the round holes are drilled a certain direction is given to the cut by making V-shaped grooves along the sides of the holes. In order that these grooves shall be made true as to line and in this plane above referred to, 25 a guide-plate is used that has in it a mortise adapted to hold the square shank of the reamer while the grooves are being cut.

In the device of this class most nearly resembling my present improvement the guide 30 is held in place by "screw-pins," and the reamer is held against the bottom of the mortise in the guide-plate by one man, the guide-plate by another, while usually two men handle hammers for driving the reamer.

35 By the use of my improved device the work of all the men, except those using the hammers, is avoided in reaming, and this saving of labor and the fact that more absolute accuracy in reaming is insured than with prior devices form the main advantages of my improvement.

My improvement consists in a guide-plate having a tubular projection on the lower side adapted to fit the drill-hole, with a square 45 mortise-opening through one edge of the guide-plate and one side of the tube, in combination with a locking device for the reamer; and it further consists in the said guide-plate with tubular extension and lateral mortise, in combination with the reamer-locking device, a

guide-pin, and a leveling-screw; and it further consists in details of the device, as more particularly hereinafter described, and pointed out in the claims.

Referring to the drawings, Figure 1 is a top 55 or plan view of my improved plate. Fig. 2 is a side view of the same, showing its method of use.

In the accompanying drawings, the letter *a* denotes a reamer, which is of usual material, 60 and is square or of an equivalent polygonal shape in cross-section, and has a groove-forming point, *a'*. The square shape of the shank or body of the reamer is preferred as being that form in which the merchantable iron or 65 steel for making the reamers may be readily procured in the markets, and it presents the proper form for holding in the mortise in the guide-plate to prevent it from rotating.

The letter *b* denotes the guide-plate, that is 70 preferably of a flat piece of metal with a tubular extension on the under side and a lateral mortise, *b'*, opening through one edge of the plate and one wall of the extension and formed to correspond to the reamer in section, the 75 latter being adapted to fit and slide in this mortise. The pin *c* projects from the under side of the guide-plate on one side of the tubular extension *b'*, and on the other side is a leveling-screw, *d*, that fits in a threaded socket 80 in the plate, with its end projecting below the plate.

The locking device *e* is composed of the sliding bolt *e'*, with its arms *e''* adapted to overlie the mortise and embrace the stud *f*, that is fast 85 to or integral with the guide-plate and is preferably made of hardened steel. The bolt *e'* is held on the plate, and in a measure guided in its sliding movement by the screw-bolt *g*, passing through the slot *e''* and through the 90 guide-plate or fast thereto. On the upper end of this screw-bolt is arranged a clamping-nut, that may be turned down upon the bolt and hold it firmly in place.

The operation of the device is as follows: 95 The tubular extension on the lower part of the guide-plate, that is preferably tapered so as to insure its fit within the drill-hole, is inserted in the latter, and the pin *c* at the same time inserted in the guide-hole, and the leveling- 100

scREW *d* is then turned until its point rests upon the surface of the rock. The bolt has been slid back to the position indicated in dotted lines in Fig. 1 before the guide-plate has been placed, as described, with the body or shank of the reamer, that has been previously fitted into the drill-hole, lying in the mortise. The bolt is then slid forward and clamped in place, the arms of the bolt, in connection with the sides of the mortise in the guide-plate and the stud *f*, forming a fixed guide for the reamer. I claim as my invention—

1. In combination with a reamer, a guide-plate having a mortise into which the polygonal-shaped shank of the reamer fits, and the locking device that holds the reamer in the mortise of the guide-plate, all substantially as described.

2. In combination with the guide-plate having the tubular extension and the mortise-

opening through the edge of the plate and the wall of the extension, the guide-pin on the lower side of the guide-plate, and the sliding bolt with the arms that engage a projection fast to the guide-plate, all substantially as described.

3. In combination with the guide-plate having the integral tubular extension, the mortise-opening through one side of the plate and of the extension, the guide-pin projecting from one end of the plate, and the leveling-screw passing through the plate at the other end, and the locking device composed of sliding bolt, clamp-screw and nut, and the lug, all substantially as described.

THOMAS MURDOCH.
